UNITED STATES PATENT OFFICE.

ROLLO MARPLE, OF CHARLOTTE, MICHIGAN, ASSIGNOR TO HANCOCK MANUFACTURING COMPANY, OF CHARLOTTE, MICHIGAN, A CORPORATION OF MICHIGAN.

DESIGN FOR A HANDLE FOR AUTOMOBILE DOORS.

Application filed March 3, 1924. Serial No. 8,803. Term of patent 3½ years.

To all whom it may concern:

Be it known that I, ROLLO MARPLE, a citizen of the United States, residing at Charlotte, in the county of Eaton, and State of Michigan, have invented a new, original, and ornamental Design for Handle for Automobile Doors, of which the following is a specification, reference being had to the accompanying drawings, forming part thereof.

Figure 1 is a front elevational view of a handle showing my design. Fig. 2 is a side view of the handle, Fig. 3 is a transverse

sectional view through the handle taken approximately in the plane of line 3—3 of Fig. 1, the stem or shank of the handle being shown in elevation.

The roughened surface herein shown in the face of the handle is of a character such as to simulate the appearance of hammered metal.

I claim:

The ornamental design for a handle for automobile doors, substantially as shown and described.

ROLLO MARPLE.
